UNITED STATES PATENT OFFICE

2,442,374

AERIAL BOMB

Bernardino Nogueira, New York, N. Y.

Application October 31, 1942, Serial No. 464,059

1 Claim. (Cl. 102—2)

1

The present invention relates to new and useful improvements in aerial bombs and the invention has for an important object to provide an armor piercing projectile carried by the bomb and adapted to be fired upon impact of the bomb with a target whereby to cause an initial penetration of the surface of the target, such as for instance, the deck of a ship, whereby to provide an opening into which the nose of the bomb may easily settle and thus materially increase the damage caused by the bomb.

A further important object of the present invention is to provide an aerial bomb which includes a cannon barrel having a bore extending therethrough for the discharge of a high powered armor piercing cartridge to initially penetrate the surface of a target and to provide firing means for the bomb in the path of the projectile for exploding the bomb subsequent to the firing of the cartridge for the projectile.

An additional object is to provide control means for the firing of the armor piercing projectile in which the projectile is held inactive during the flight of the bomb and in which the discharging movement of the projectile is initially caused by the inertia resulting from the bomb striking the target to start the projectile in its flight and in which the initial movement of the projectile actuates a firing mechanism for a cartridge carried by the bomb for firing the projectile.

A still further object is to provide an apparatus of this character of simple and practical construction, which is efficient and reliable in performance, relatively inexpensive to manufacture, which embodies safety features to prevent accidental discharge of the bomb while handling and which otherwise is well adapted for the purposes for which the same is intended.

Other objects and advantages reside in the details of construction and operation as more fully hereinafter described and claimed, reference being had to the accompanying drawings forming part hereof, wherein like numerals refer to like parts throughout and in which—

Figure 1 is a side elevational view.

Figure 2a is a fragmentary longitudinal sectional view through the tail or rear end of the bomb.

Figure 2b is a similar view of the nose or front end of the bomb.

Figure 3 is an enlarged fragmentary longitudinal sectional view of the firing mechanism for the armor piercing projectile.

Figure 4 is a transverse sectional view taken substantially on a line 4—4 of Figure 2a.

2

Figure 5 is a similar view taken substantially on a line 5—5 of Figure 2b.

Figure 6 is a transverse sectional view taken substantially on a line 6—6 of Figure 3.

5 Figure 7 is a detail of the safety locking pin of the armor piercing projectile.

Figure 8 is an end elevational view of the armor piercing nose cap showing the saw cuts therein.

10 Figure 9 is an enlarged detail of the firing device.

Referring now to the drawings in detail wherein for the purpose of illustration I have disclosed a preferred embodiment of the invention, the numeral 5 designates the principal body of the bomb which is of cylindrical shape and of hollow construction tapering at one end to form the nose 6. The nose is formed with a bore 7 extending through the tip thereof and registering with the bore 8 of a cannon barrel 9 extending longitudinally in the body and supported in spaced relation from the walls thereof by fins 10.

The rear end of the body 5 is closed by a breech block 11 in which the rear end of the cannon barrel is recessed as shown to advantage in Figure 2a of the drawings.

The breech block is rounded and has fitted thereto a tail member 12 of substantially conical shape and includes the longitudinally extending stabilizer fins 13 connected at their rear ends by a ring member 14.

The nose 6 is formed with a plurality of rearwardly inclined vent passages 15 and fitted over the nose is a cap 16 which may be soldered or otherwise temporarily secured to the nose 6, the outer end of the cap being of generally rounded blunt construction and formed with intersecting saw cuts 17 extending partly along the sides of the cap, the saw cuts permitting spreading or

40 mushrooming of the segments 19 formed between the saw cuts upon the striking of the bomb with a target or object. The saw cuts are closed by means of relatively light strips of metal 18 and secured in position by soldering or the like to prevent oxidation or deterioration of the interior of the cap. Between the front end of the cap and the front end of the nose 6 is a cork or wooden plug 20 closing the outer end of the bore 7.

45 The side walls of the cap are also formed with vent openings 21 in the region of the openings 15 and spacing fins 16' are formed on the interior of the cap.

The breech block 11 is formed with a recess 22 in which is conformably fitted a cartridge 23

having an explosive charge positioned in the chamber 24 thereof.

The outer end of the cartridge 23 is closed by an end wall 25 having a slotted guide 26 therein. Inwardly of the end wall 25 is a partition 27 forming a chamber 28 in the outer end of the cartridge, the end wall 25 and partition 27 preferably being made of plastic combustible material.

A pair of firing caps 29 are positioned in the chamber 28 adjacent the guide 26 and leading from the firing caps are a pair of fuse members 30 communicating with a detonator cap 31 positioned in the cartridge 23 for firing the charge.

Flanges 32 project laterally from opposite sides of the cartridge in the plane of the end wall 25, the flanges being seated in the inner ends of longitudinal slots 33 formed in the breech block. Plugs 34 are positioned in the slots bearing against the flanges 32, the plugs being secured in position by screws 35.

An armor piercing projectile 36 is positioned in the cannon barrel 9 and is provided at its inner end with a longitudinally extending pin 37 having a cross head 38, the pin extending through the guide 26 while the cross head 38 is positioned in the chamber 28.

The cross head 38 is inserted through the slot of the guide 26 during assembly of the projectile and is given a ninety degree turn to bring the pointed ends 39 of the cross head into position for striking the firing caps 29 upon the initial outward movement of the projectile.

A pair of shear pins 40 of copper or other soft metal project laterally from diametrically opposite sides of the projectile and are adapted to enter bayonet slots 41 formed in the outer end of the breech block 11, one end of the bayonet slots having an entrance slot 42 for receiving the ends of the pins 40 and the bayonet slots having a flange 43 under which the ends of the pins are adapted to ride during the assembly of the projectile in position in the breech block. After the projectile has been assembled and the pins moved into the end of the bayonet slots 41 as shown to advantage in Figure 6 of the drawings, the slots 41 may be closed by a thin metal plate 44.

The bore 8 of the cannon barrel 9 is smooth bore and the projectile 36 is formed with piston rings 45. After the armor piercing projectile 36 and the cartridge 23 have been assembled in position in the cannon barrel and the breech block, the breech block is secured in position to the body 5 by means of screws 46.

The projectile is secured in position with the cross member 38 spaced from the firing caps 29 by means of the shear pins 40 and also secured against accidental displacement by a safety pin 47 extending outwardly through the cannon barrel as well as through the breech block and the side walls of the body with its inner end adapted to enter a recess 48 in the side of the projectile. The pin 47 is formed with a collar 49 against which a coil spring 50 abuts for retracting the pin. The outer end of the pin 47 is slidably mounted in an apertured plug 51 to the outer end of which is formed a guide 52 receiving a locking pin 53 extending transversely of the pin 47 to prevent retracting movement thereof. The locking pin 53 has a chain 54 attached thereto for connection with a stationary part of an aeroplane in which the bomb is loaded whereby upon releasing of the bomb for discharge from the aeroplane in the usual manner the locking pin 53 will be withdrawn to permit retraction of the

safety pin 47 in a manner as will be apparent.

The principal body 5 is adapted to carry the main explosive charge in the space surrounding the cannon barrel 9 and the main explosive charge 5 is fired by a detonator of conventional construction indicated at 55 in Figure 2b and Figure 9 of the drawings which is positioned in a light metal casing 56 secured in the front end of the body to one of the fins 10 by the ears 57. The detonator 55 is connected by means of a fuse 58 leading to a firing cap 59 mounted in a plug 59' in the nose of the body. The firing cap 59 is in the path of a firing pin 60 having one end beveled and projected into the bore 8 of the cannon barrel by means of a coil spring 61. A safety wire 62 is connected to the outer end of the firing pin 60 and soldered to the wall of the bore 8 to prevent accidental firing movement of the pin 60 during handling of the bomb.

In the operation of the device after the locking pin 53 has been withdrawn by the gravitation of the bomb during its initial discharge from the aeroplane the safety pin 47 is then retracted by the spring 50 to permit the projectile 36 to be fired.

Upon impact of the bomb with the target, such as the deck of a ship, the nose cap 16, upon striking the target will open and a sudden interruption in the flight of the bomb will cause the weight of the projectile 36 to shear the pins 40 and move the prongs 39 of the cross member 38 into striking engagement with the firing caps 29 whereby to explode the cartridge 23 and fire the projectile through the cannon barrel into the target to form an opening therein.

The end of the nose 6 tapers to a substantially sharpened point permitting the nose of the bomb to settle into opening caused by the projectile 36, and this entering movement of the bomb is aided by the lateral support and guidance given by the nose cap 16.

As the projectile 36 passes through the outer end of the bore 8 of the cannon barrel 9 the firing pin 60 will be actuated whereby to fire the main charge through the delayed action of the fuse 58.

From the foregoing it will be appreciated that the interruption in the flight of the bomb when striking its target, will cause initial discharging movement of the armor piercing projectile, which is then accelerated by the firing of the cartridge.

It is believed the details of construction, advantages and manner of use of the device will be readily understood from the foregoing without further detailed explanation.

Having described the invention, what is claimed as new is:

An aerial bomb comprising an elongated hollow body having at one end a pointed nose provided with an open axial bore, a barrel mounted in the body axially of the latter and having an axial bore aligned with the bore of said nose, a bursting explosive charge for the body disposed within the latter and about the barrel, stabilizer fins on the other end of the body, an armor piercing projectile mounted in the barrel for discharge through said nose, an explosive charge for firing the projectile from the barrel, igniting means for the second-named explosive charge including a firing cap, a firing member attached to and movable with the projectile for striking said firing cap and causing firing of the projectile upon movement of the latter under the force of inertia due to impact of the bomb with a target, means including a firing pin operated by the projectile in its passage from the barrel for igniting said

bursting charge, and frangible means for preventing movement of the projectile until the bomb impacts the target.

BERNARDINO NOGUEIRA.
